(57) **CLAIM**

The ornamental design for a utility knife, as shown.

DESCRIPTION

FIG. 1 is a perspective view of a utility knife showing my new design;

FIG. 2 is a front end view thereof;

FIG. 3 is a rear end view thereof;

FIG. 4 is a right side view thereof;

FIG. 5 is a top plan view thereof; and,

FIG. 6 is another perspective view of the utility knife with the blade being extended therefrom.

The broken lines illustrate portions of the design that form no part of the claimed design.
